UNITED STATES PATENT OFFICE

2,053,973

ELECTRIC CIRCUIT INTERRUPTER

Motooki Shinohara, Tokyo, Japan, assignor to
 General Electric Company, a corporation of
 New York

Application July 26, 1934, Serial No. 737,067
 In Japan October 26, 1933

2 Claims. (Cl. 200—150)

My invention relates to electric circuit interrupters, more particularly to those of the so-called explosion chamber type and has for its principal object the provision of an improved 5 circuit interrupter of the aforesaid type which shall have increased interrupting capacity and be simple and compact in construction and efficient in operation.

My invention will be more fully set forth in the 10 following description referring to the accompanying drawing, and the features of novelty which characterize my invention will be pointed out with particularity in the claims annexed to and forming a part of this specification.

Referring to the drawing, Fig. 1 is an elevational view, partly in section, of the contact and explosion chamber structure of an electric circuit interrupter embodying my invention, and Fig. 2 is a similar view of another form my 15 invention may assume.

In Fig. 1 is shown the contact and explosion chamber structure comprising one pole of an electric circuit interrupter of the well-known double-break type. A circuit interrupter of this type 20 generally comprises a tank containing a suitable arc extinguishing or insulating liquid as oil in which both poles of the contact structure are immersed, the movable contact structure comprising a contact bridging member which is adapted 25 to engage and interconnect the stationary contact structure of both poles and to be lowered into the arc extinguishing liquid when the circuit is to be opened.

Referring more particularly to Fig. 1 the stationary contact structure 1 coacts with a movable rod contact 2 within an explosion chamber 3 formed by an insulating casing 4 which is composed of material suitable for withstanding high bursting pressures. The casing 4 at its lower 30 end is provided with an exhaust passage 5 through which the movable contact 2 is operated in opening and closing the circuit.

In the operation of an explosion chamber circuit interrupter of the conventional type the 35 pressure generated within the chamber by an arc drawn in the arc extinguishing liquid between the separating contacts is effective to direct a blast of said liquid through the explosion chamber exhaust passage and through the arc at said passage when the movable contact has cleared the same. Obviously the arc may be drawn throughout the length of the explosion chamber before it is subjected to the arc extinguishing blast.

For the purpose of also subjecting the arc to a 40 blast of the extinguishing liquid shortly after

separation of the contacts, means are provided for directly venting the explosion chamber 3 to a region of comparatively low pressure at the point where separation of contact structures 1 and 2 occurs. To this end the contact structure 1 is arranged to form a central passage 6 which is closed by the rod contact 2 in the closed circuit position and which serves as a second exhaust passage for the explosion chamber 3 upon the separation of contacts 1 and 2.

In the specific arrangement shown a stationary adapter 1 of conducting material is provided with a plate-like or flange portion 7' which not only supports the stationary contact structure 1 but also the insulating casing or explosion pot 4 as indicated at 8 and also forms the upper wall of the explosion chamber. The contact structure 1 may comprise an annular conducting retainer member 9 suitably secured as by rings 10 in the wall 7' of the explosion chamber and a plurality 15 of contact segments 11 which are positioned radially with respect to the rod contact 2 within the retainer 9 and are resiliently biased into contact engagement with rod 2 as by garter springs 12.

The circuit opening operation is effected by 20 lowering of the rod contact 2 into the main oil body exteriorly of the explosion chamber so that both exhaust passages 5 and 6 of the explosion chamber are cleared.

Upon initial separation of the contacts within 25 the explosion chamber, the arc decomposes the oil in the explosion chamber at a high rate, generating gas which creates a high pressure within the chamber. The resulting pressure is effective to direct a blast of oil through the exhaust passage 6 and radially through the arc formed between the contacts 1 and 2. Accordingly immediately upon separation of the contacts the resulting arc is subjected to an oil blast from the explosion chamber. In the event that the arc 30 is not interrupted when the rod contact 2 clears the exhaust passage 5, the pressure within the explosion chamber is effective to direct a second blast of oil through the arc at the exhaust passage 5. The arc is therefore subjected to an oil blast both at the initiation of arcing and at the time when the movable contact leaves the explosion chamber.

Fig. 2 illustrates another arrangement wherein 35 the arc is subjected to a blast of arc extinguishing liquid at the time of contact separation and also when the movable rod contact leaves the explosion chamber. The insulating explosion pot 4, as in the previous instance, is supported by a 40

plate-like conducting member 15 forming part of the adapter structure 16. The explosion pot 4 is provided with an insulating partition 17 forming the upper wall of the explosion chamber 18 through the exhaust passage 19 of which the movable rod contact 20 operates. The coating contact 21 is mounted within the central opening in the partition 17 and is resiliently biased as by a spring 22 to the position limited by the flange 23. The contact 21 is electrically connected as by a flexible lead 24 to the portion 15 of the adapter.

For the purpose of forming a second exhaust passage for venting the explosion chamber 18 directly to a region of comparatively low pressure, the contact 21 is provided with a central passage and communicating ports 25 and 26 respectively opening above the partition 17. The explosion pot is likewise provided with exhaust ports 27 so that in the position of the circuit interrupter illustrated there exist exhaust passages between the explosion chamber 18 and the exterior surrounding oil body.

The movable rod contact 20 is provided with a conical contact portion 20' which engages a corresponding contact surface 21' at the lower end of the contact 21 so that in the closed circuit position the exhaust passage 25 is substantially closed. Upon circuit opening movement the contact 21, by reason of its resilient mounting, remains in following contact engagement to the position shown and the arc initially drawn within the explosion chamber 18 is immediately subjected to a blast of oil from the chamber through the exhaust passage 25. As in the previous case the arc, if not already interrupted, is subjected to a second oil blast in passing through the exhaust passage 19.

It should be understood that my invention is not limited to specific details of construction and arrangement thereof herein illustrated, and that changes and modifications may occur to one skilled in the art without departing from the spirit of my invention.

What I claim as new and desire to secure by Letters Patent of the United States, is:—

1. An electric circuit interrupter comprising an insulating casing forming an explosion chamber having an exhaust passage, said casing being immersed in an arc-extinguishing liquid, a fixed contact mounted in the upper wall of said chamber and forming a second exhaust passage for said chamber terminating beneath the level of said liquid, said second exhaust passage being unobstructed and short as compared with the length of said chamber so that liquid may exhaust freely from said chamber without appreciable back pressure, and a coating rod contact movable through said first-named exhaust passage for engaging said fixed contact at said second exhaust passage, said rod contact clearing both of said exhaust passages in moving to open circuit position so that arc pressure in said chamber is effective to direct in sequence an arc-extinguishing blast of liquid through each of said passages.

2. An electric circuit interrupter comprising an insulating casing having a partition forming an explosion chamber and a pressure relief chamber, said casing being immersed in an arc-extinguishing liquid, said explosion chamber having an exhaust passage venting directly exteriorly of said casing and a second exhaust passage in said partition, a relatively fixed contact forming a fluid passage between said chambers mounted in said second exhaust passage and resiliently biased so as to seat therein, said pressure relief chamber having unobstructed openings directly venting said chamber exteriorly of said casing so that liquid may exhaust freely from said explosion chamber by way of said second exhaust passage without appreciable back pressure, and a coating rod contact movable through said first exhaust passage for engaging said fixed contact, said rod contact clearing both of said exhaust passages in moving to open circuit position so that arc pressure in said chamber is effective to direct in sequence an arc-extinguishing blast through each of said passages.
